UNITED STATES PATENT OFFICE.

ROBERT HENRY CROZIER, OF LONDON, ENGLAND.

FRACTIONATION OF HYDROCARBON OILS AND LIKE LIQUIDS.

Application filed July 7, 1925. Serial No. 41,976.

To all whom it may concern:

Be it known that I, ROBERT HENRY CROZIER, a subject of the King of Great Britain and Northern Ireland, and residing at London, England, have invented a certain new and useful Improvement in Fractionation of Hydrocarbon Oils and like Liquids, of which the following is a specification.

This invention relates to improvements in and connected with the fractionation of hydrocarbon oils and like liquids.

In accordance with the invention the vapours to be treated and coming from a retort or a still are subjected to temperature control by passing them upward through columns traversed by pipes containing steam or hot fluid at a desired temperature and then downward through cooling columns traversed by pipes containing water or other cooling fluid of desired temperature, there being provided beneath all of these columns or beneath a number of them only condensing or collecting boxes in which condensate from the respective columns is collected and from which it may be withdrawn, if desired, partitions being arranged to extend into some of the collecting boxes so as to ensure that the vapours shall follow the path through the columns. In addition to these partitions baffle plates may be arranged to extend just below the level of the liquid in the collecting boxes so as to cause the vapours to bubble through the condensate.

The invention is illustrated in the accompanying drawing in which Fig. 1 and Fig. 2 are diagrammatic views at right angles to one another of apparatus in accordance with the invention. Fig. 3 is a detail view of one of the baffles. Fig. 4 a diagram illustrative of a convenient arrangement of a series of such fractionating apparatus while Fig. 5 is a diagrammatic representation at right angles to Fig. 4 showing the connections between the collecting boxes of the series.

In the drawing 1 is a collecting box which may be heated externally and to which the vapours from a retort or still (not shown) are supplied by means of a pipe 2 formed at its outlet with a serrated edge 3. This collecting box 1 is in communication with the columns in which the vapours are treated. The columns A through which the vapours pass upwards are heated by means of internal steam coils B. C indicates the columns cooled by water circulated through the internal coils D, down through which columns

C pass the vapours which have risen through the columns A. Condensate deposited in the columns is collected in condensing or collecting boxes or compartments E open to the lower ends of the columns. These compartments are fitted with draw-off cocks e, and are disposed in cascade relation, so that, if desired, the condensate may cascade from one compartment to the next, partitions F being fitted in the boxes, so that the vapours have no other path than that through the columns. The coils B for the several columns A are shown as interconnected as are also the coils D for the other columns C so that the steam or the water will pass from one heating or cooling column to the others in succession.

The partitions F disposed within the boxes or compartments E are of such depth as to extend below the normal liquid level in such boxes so as to afford a gas seal while permitting free flow of the condensate from one compartment to another in the event that it is not desired to withdraw the liquid product from any particular compartment. In addition to the partitions F there may be provided baffles G extending just below the liquid level in the respective boxes, the baffles G being each suitably formed with a serrated lower edge to permit the vapours to bubble through the condensate. As the volume of gas increases and the liquid level $\alpha-\alpha$ in the boxes is depressed, the serrations in the lower edges of the baffles G present a larger area for the gases to bubble through the condensate. For conducting the vapours past the first partition F encountered by them a by-pass K is provided. The vapours from the last column of the series are drawn off through a scrubber in order to remove the light spirit and ammonia present, the remainder of the vapours or gases being used as fuel.

In practice I may employ series of such fractionating condenser units, each associated with a vapour pipe of an oil still or of a retort.

I have illustrated such an arrangement in Fig. 4. As shown therein, a series of such units is so arranged that the unvolatilized condensate from the primary collecting box 1 of each unit can flow through the pipe H to the primary collecting box of the next hottest unit in the series and the lightest fractions collected in the cold terminal box L of the last unit in the series are led back

through pipes M to the primary collecting box 1 of the preceding unit, wherein the temperature maintained is approximately the boiling point of the condensate in the terminal box L connected thereto.

If desired, in order to accelerate the volatilization of lighter fractions, steam may be admitted into any of the collecting boxes at any part or into the box 1, or at any other point before said fractions reach the first separating column. Heat may be applied externally to the box 1 in order to maintain a definite temperature.

It will be seen that by supplying steam of definite or fairly definite temperature to the coils in those columns through which the vapours are led in an upward direction the possibility of low boiling point fractions condensing at parts of the plant where such condensation is not desired is avoided. The temperature conditions of all the columns can be regulated independently of one another, if desired.

It will be seen also that the arrangement of the apparatus permits of rectification by returning the condensate in contact with the hotter incoming vapours.

What I claim is:—

1. Apparatus for the fractionation of hydrocarbon oils and like liquids including columns through which the vapours to be treated may pass serially upwards, pipes containing heating medium and traversing said columns, columns alternating with said first-mentioned columns through which the vapours may pass serially downwards, pipes containing cooling medium and traversing said second-mentioned columns, a connection between each column of the first series and a column of the second series, means connecting the pipes containing cooling medium serially and means connecting the pipes containing heating medium serially and condensate collecting boxes disposed beneath and open to the lower ends of at least some of said columns.

2. Apparatus for the fractionation of hydrocarbon oils and like liquids, including columns for upward passage of the vapours to be treated, heating pipes traversing said columns, columns alternating with said first-mentioned columns and serving for downward passage of the vapours, cooling pipes traversing said second-mentioned columns, means connecting said heating pipes serially and means connecting said cooling pipes serially, condensate collecting boxes disposed beneath and open to the lower ends of at least some of said columns, and partitions in said collecting boxes serving to confine the vapours to flow from one column to the next column.

3. Apparatus for the fractionation of hydrocarbon oils and like liquids, including columns through which the vapours may

pass upwardly, heating pipes traversing said columns, columns through which the vapours may pass downwardly, cooling pipes traversing said second-mentioned columns, condensate collecting boxes disposed in cascade beneath and open to the lower ends of said columns, and baffle plates having serrations on their lower edges, the upper edges of the serrations being level with the upper edge of the associated collecting box, substantially as and for the purpose set forth.

4. Apparatus for the fractionation of hydrocarbon oils and like liquids, including a plurality of columns through which the vapours may pass serially upwards, pipes containing heating medium traversing said columns, a plurality of columns through which the vapours may pass serially downwards, pipes containing cooling medium traversing said second-mentioned columns, condensate collecting boxes disposed beneath and open to the lower end of said columns, partitions extending into said collecting boxes and serving to control the flow of the vapours from one column to another, and baffle plates one for each of at least certain of the collecting boxes, said baffle plates having serrations on their lower edges, the upper edges of said serrations being level with the upper edge of the associated collecting box, substantially as and for the purpose set forth.

5. Apparatus for the fractionation of hydrocarbon oils and like liquids, including a series of columns serving for upward passage of vapours, heating coils traversing said columns, a series of columns alternating with said first-mentioned columns and serving for downward passage of vapours, cooling coils traversing said second-mentioned columns, a connection between the upper end of each column of the first series and a column of the second series, means connecting said heating coils serially, means connecting said cooling coils serially, and condensate collecting boxes disposed in cascade open to the ends of said columns.

6. Apparatus for the fractionation of hydrocarbon oils and like liquids including a series of columns for upward passage of vapours, a series of columns alternating with said first-mentioned columns for downward passage of vapours that have passed upwardly through said first-mentioned columns, pipes containing heating medium traversing the first series of columns, pipes containing cooling medium traversing the second series of columns, means connecting the pipes containing heating medium serially, means connecting the pipes containing cooling medium serially, a row of collecting boxes arranged in cascade disposed beneath and open to the lower ends of said columns, and a hydrocarbon vapour supply connection to the end box of the row.

7. Apparatus for the fractionation of hydrocarbon oils and like liquids including a series of columns for upward passage of vapours, a series of columns alternating with said first-mentioned columns for downward passage of vapours that have passed upwardly through said first-mentioned columns, pipes containing heating medium traversing the first series of columns, pipes containing cooling medium traversing the second series of columns, means connecting the pipes containing heating medium serially, means connecting the pipes containing cooling medium serially, a row of collecting boxes arranged in cascade disposed beneath and open to the lower ends of said columns, an outflow for the end box of the row, and a hydrocarbon vapour supply connection to the end box of the row, said connection extending just below the level of the outflow in said end box and having a serrated lower edge.

10 8. Apparatus for the fractionation of hydrocarbon oils and like liquids including a series of columns for upward passage of vapours, a series of columns alternating with said first-mentioned columns for downward passage of vapours that have passed upwardly through said first-mentioned columns, pipes containing heating medium traversing the first series of columns, pipes containing cooling medium traversing the second series of columns, a row of collecting

boxes arranged in cascade disposed beneath and open to the lower ends of said columns, an outflow for the end box of the row, and a hydrocarbon vapour supply connection to the end box of the row, said connection extending just below the level of the outflow in said end box and having a serrated lower edge.

15 9. Apparatus for the fractionation of hydrocarbon oils and like liquids, including a series of fractionating condenser units, each unit comprising a plurality of heated columns and a plurality of cooled columns alternating therewith through which vapours may be passed serially, and collecting boxes beneath the columns in each unit to receive separately condensates of different boiling points, said boxes including a primary collecting box which serves to receive the material to be fractionated and a terminal box to receive the condensate of lowest boiling point, pipe connections between the terminal boxes and primary boxes of different units for leading condensate from the terminal boxes to the connected primary boxes, and connections for leading the residues in each primary box to another primary box.

20 In testimony whereof I have signed my name to this specification.

R. H. CROZIER.
